United States Patent Office

Des. 178,880
Patented Oct. 2, 1956

178,880

COMBINED SEAT AND BACK

Jon W. Hauser, St. Charles, Ill., assignor to Hawley
Products Company, St. Charles, Ill., a corporation of
Delaware

Application February 1, 1956, Serial No. 39,994

Term of patent 14 years

(Cl. D15—8)

FIG. 1

FIG. 2

FIG. 3

FIG. 4

Fig. 1 is a side elevational view of a combined seat and back, embodying my new design;

Fig. 2 is a front elevational view thereof;

Fig. 3 is a rear elevational view thereof; and

Fig. 4 is a top plan view thereof.

I claim:

The ornamental design for a combined seat and back, as shown.
